RACK

Maurice Duchin, New York, N. Y.

Application August 2, 1954, Serial No. 31,696

Term of patent 7 years

(Cl. D33—3)

The single figure in the drawing is a perspective view of a rack showing my new design.

The essential features of my design reside in the parts shown in solid black lines.

I claim:

The ornamental design for a rack, substantially as shown and described.
